UNITED STATES PATENT OFFICE.

BENJAMIN F. HUBBELL, OF CAMBRIDGE, MASSACHUSETTS, ASSIGNOR, BY MESNE ASSIGNMENTS, TO THE BASSICK MANUFACTURING COMPANY, OF CHICAGO, ILLINOIS, A CORPORATION OF DELAWARE.

LUBRICATING APPARATUS.

Application filed March 14, 1922. Serial No. 543,553.

This invention pertains to improvements in lubricating apparatus. It is among the objects of the invention to provide a source of lubricant under pressure which may be conveniently attached to and detached from a lubricant-receiving part.

In the drawings, which show a preferred form of one embodiment of my invention:

Figure 1 is a side elevation of a preferred form of grease gun coupled to a grease-receiving nipple;

Fig. 2 is a longitudinal central section through the gun illustrated in Fig. 1, being partly in elevation;

Fig. 3 is a side elevation of the nozzle portion of the apparatus illustrated in Figs. 1 and 2, being partly broken away to show the grease-receiving nipple entered therein, but prior to completion of the coupling operation;

Fig. 4 is an end elevation of the discharge end of the apparatus;

Fig. 5 is a view similar to Fig. 3, but showing the relation of the parts at the completion of the coupling operation;

Fig. 6 illustrates the preferred form of sealing part shown in section in Fig. 2, showing three views, these being respectively left end elevation, side elevation and right end elevation;

Fig. 7 illustrates a preferred form of one of the sealing washers illustrated in Fig. 2;

Fig. 8 is a rear elevation of that portion of the valve mechanism illustrated in Fig. 2 which is rotated relative to the grease-receiving part during the valve opening operation;

Fig. 9 shows an end elevation and longitudinal section (partly in elevation) of a preferred form of grease-receiving nipple illustrated in Figs. 1 through 4;

Figs. 10 and 11 are diagrammatic views illustrating the relative position of the various cooperating parts lying at the left of the line 10-10 on Fig. 2, the views showing the relative position of the parts both prior and subsequent to the coupling and valve opening operations; and

Fig. 12 is a view showing the parts in the relative position shown in Fig. 5, the section taken diagonally of the nipple.

Referring to the drawings and to the preferred form of my invention selected for illustrative purposes, I have shown a lubri-

cant-expelling device including a barrel 12, 55 and a plunger 13 adapted to be actuated therein to expel lubricant in the usual manner by rotation of the screw-threaded stem 14. The discharge end of the preferred form of my invention illustrated includes a 60 nozzle or end piece 15 apertured at one end to receive a head of a lubricant-receiving nipple 16 which may be of any desired shape, but which is preferably enlarged at 17 to provide extended lateral faces and 65 underlying surfaces beneath which flanged portions on the nozzle 15 may engage when the nipple is entered in the nozzle and the nozzle is turned relative thereto. Operatively enclosed within the nozzle 15, I have 70 provided a sealing part 18 adapted to be moved axially of the nozzle during the coupling and uncoupling operation so that when the nipple 16 is entered in the nozzle 15 a clearance may be provided, this clearance being taken up, pursuant to the coupling operation, by rotation of the nozzle 15 relative to the lubricant-receiving nipple 75 and relative to the sealing part 18, which is held by the grease-receiving nipple against 80 rotation or turning movement with the nozzle 15. The sealing part 18 may conveniently carry a sealing disc or washer 19 apertured to permit passage of lubricant 85 therethrough, and the rotation between the sealing part 18 and cooperating portions of the mechanism, herein shown as the valve disc 20, may conveniently be used to provide a valve for permitting the discharge of lubricant pursuant to the coupling operation 90 and preventing the discharge of lubricant 95 when the nipple is not coupled to the nozzle. In the preferred form of apparatus illustrated, the nozzle 15 is chambered internally to provide flanges 21 adapted to underlie 100 the projections 17 on the lubricant-receiving nipple when coupled, and inclined means operatively engaged with the sealing part 18, this inclined means being typified by the female thread 22 in the nozzle into which the male thread 23 of the sealing part enters. The thread is preferably so proportioned and of such pitch that when the nipple is entered in the nozzle, the underlying face of the projection 17 will considerably overlie the flange 21, thus providing ample clearance to permit easy passing 105 of the projecting portions of the nipple over

the flanges on the nozzle, and so that as the nozzle is turned relative to the nipple the sealing part 18 cannot turn relative thereto, being held by engagement of the projections 5 24 and 25 (Fig. 6) over the lateral faces of the enlarged portion of the nipple. The sealing part 18 being held against rotation and being threaded or otherwise engaged by inclined means to the nozzle 15 will be 10 moved toward the end of the nipple (or the flanges on the end of the nozzle will be drawn rearwardly toward the under side of the projection 17 on the nipple) thus taking up the clearance and pressing the sealing 15 part, with interposed sealing washer 19, against the lubricant-receiving end 26 of the nipple, the extent of pressure being determined by the pitch of the inclined means and by the torque on the nozzle 15, 20 the latter torque in the form of my invention illustrated being the same as the torque on the barrel of the lubricant-expelling device.

To provide for registration of the 25 projections 24 and 25 with the lateral faces of the opening in the end of the nozzle 15 so as to permit ready entrance and removal of the nipple relative to the nozzle of the apparatus, I have provided stop means herein 30 typified by the screw or pin 27 carried by the sealing part 18 and cooperating with a stop surface typified by the end 28 of a slot in the nozzle. The extent of relative rotation between the nozzle 15 and sealing 35 part 18 is therefore determined in one direction, herein shown as the right hand direction, by the pressure of the sealing part on the end of the nipple, this pressure being opposed by the flanges on the nozzle underlying the projections on the nipple. On the 40 other hand, when the parts are rotated in the left hand direction, the extent of rotation or turning movement between the nozzle 15 and the sealing part 18 is limited by the 45 engagement of the projection 27 with the end 28 of the slot in the nozzle in which position no portion of the projection 17 on the nipple will overlie the flanges 21 of the nozzle, thus permitting ready withdrawal of 50 the nozzle from the nipple.

The preferred form of valve illustrated is of the rotary type, ports 30, 31 in the rotatable valve part 20 registering with passages in the sealing part 18 pursuant to the 55 coupling operation. In practice, I have found that the point at which an adequate seal between the sealing part and the nipple is reached will not vary sufficiently to cause nonregistration of the valve parts, but I 60 may provide for variations in thickness of the sealing disc by elongation of the apertures in the valve disc. It will be understood that the valve part 20 reciprocates axially of the apparatus as the sealing part 65 18 reciprocates, always remaining in close

contact therewith because of the pressure of the lubricant when any lubricant under pressure is contained in the apparatus. When the apparatus is empty of lubricant, the disc 20 cannot become substantially displaced because generally located by the shoulder 40 on the head 41 of the barrel. To oppose leakage past the inclined means or threads on the sealing part 18, I have provided a sealing washer 42 which may be 75 fixed relative to the nozzle 15 permitting the smooth rear end of the sealing part 18 to be reciprocated therethrough during the coupling and uncoupling operations.

While I have shown and described a preferred form of one embodiment of my invention, it will be understood that changes involving omission, substitution, alteration and reversal of parts, and even changes in the mode of operation, may be made without departing from the scope of my invention, which is best defined in the following claims.

I claim:

1. Lubricating apparatus comprising, in combination, a lubricant-receiving nipple and a lubricant-expelling device having a coupling at its discharge end, said coupling axially receiving said nipple while providing axial clearance prior to completion of the coupling operation, a gasket and means held against rotation relative to said nipple during the coupling operation for taking up said clearance by positively moving said gasket toward said nipple thereby providing a tight joint with the lubricant-receiving end of said nipple.

2. Lubricating apparatus comprising, in combination, a lubricant-receiving nipple presenting a polygonal portion and a lubricant-expelling device having a coupling at its discharge end, said coupling having polygonally apertured means to receive and retain said polygonal portion and providing axial clearance prior to completion of the coupling operation, and screw-operated means for taking up said clearance and providing a tight joint with the lubricant-receiving end of said nipple.

3. Lubricating apparatus comprising, in combination, a lubricant-receiving nipple presenting a polygonal portion and a lubricant-expelling device having a coupling at its discharge end, said coupling having polygonally apertured means to receive and retain said polygonal portion and providing axial clearance prior to completion of the coupling operation, and inclined plane operated means for taking up said clearance and providing a tight joint with the lubricant-receiving end of said nipple.

4. Lubricating apparatus comprising, in combination, a lubricant-receiving nipple presenting a polygonal portion and a lubricant-expelling device having a coupling at

- its discharge end, said coupling receiving said polygonal portion of said nipple while providing axial clearance prior to completion of the coupling operation, and a sealing part held against rotation relative to said nipple when the latter is entered in said coupling, said coupling providing a nipple gripping end and means actuated by rotative movement for taking up the clearance and moving toward each other said sealing part and said end.
5. Lubricating apparatus comprising, in combination, a lubricant-receiving nipple having lateral projections, a grease gun having a discharge end fixedly connected thereto, said discharge end providing an opening at its end to admit an end of said nipple including said lateral projections, said discharge end also providing adjacent said opening flange portions to engage beneath said lateral projections when said discharge end is turned relative to said nipple and also providing an interior movable part and inclined means for moving said interior movable part toward said nipple to provide a sealed joint therewith when coupled and from said nipple to provide clearance for entrance and removal of said nipple when not coupled.
10. In a pressure lubricating system, a lubricant-receiving nipple, and a source of lubricant under pressure having means for coupling thereof to said nipple by rotative movement to form a seal, a valve operatively interposed in the path of said lubricant adjacent said coupling and presenting parts providing apertures brought into and out of alignment by relative rotation, at least one of said apertures enlarged to compensate for variation in the extent of rotation therebetween during the coupling operation.
11. Lubricating apparatus including a nozzle having means for receiving and retaining a lubricant-receiving nipple, sealing means housed inside said nozzle and engaging said nipple when inserted to prevent rotation of said sealing means relative to said nipple, said sealing means being actuated by rotation of said nozzle relative to said nipple to move forward against said nipple and form a seal, and ported valve means axially slideable in said nozzle but rotating therewith, said valve means abutting said sealing member and said sealing member having ports positioned to register with said valve ports only after said seal has been formed.
12. Lubricating apparatus including a nozzle having means for receiving and retaining a lubricant-receiving nipple, and sealing means housed inside said nozzle and engaging said nipple when inserted to prevent rotation of said sealing means relative to said nipple, said sealing means being actuated by rotation of said nozzle relative to said nipple to move forward against said nipple and form a seal, and valve means in said nozzle positioned to open only after said seal has been formed.
13. Lubricating apparatus including a nozzle having means for receiving a lubricant-receiving nipple, and sealing means housed inside said nozzle and engaging said nipple when inserted to prevent rotation of said sealing means relative to said nipple, said sealing means being actuated by rotation of said nozzle relative to said nipple to move
- its discharge end, said coupling receiving said polygonal portion of said nipple while providing axial clearance prior to completion of the coupling operation, and a sealing part held against rotation relative to said nipple when the latter is entered in said coupling, said coupling providing a nipple gripping end and means actuated by rotative movement for taking up the clearance and moving toward each other said sealing part and said end.
9. Lubricating apparatus comprising, in combination, a nipple having a lubricant-receiving aperture at one end and providing lateral projections, and a lubricant-expelling gun having a nozzle presenting nipple-engaging portions 21, a reciprocable sealing part 18 and inclined means independent of said nipple-engaging portions for causing reciprocation of said sealing part 18 relative to said nipple-engaging portions 21 during engagement and disengagement of the nozzle with the nipple.
10. Lubricating apparatus comprising, in combination, a nipple having a lubricant-receiving aperture at one end and providing lateral projections, and a lubricant-expelling gun having a nozzle presenting nipple-engaging portions 21, a reciprocable sealing part 18 and inclined means independent of said nipple-engaging portions for causing reciprocation of said sealing part 18 relative to said nipple-engaging portions 21 during engagement and disengagement of the nozzle with the nipple, said sealing part 18 apertured to permit passage of lubricant therethrough and cooperating with a valve part to control passage of lubricant therethrough.
11. Lubricating apparatus including a nozzle having means for receiving and retaining a lubricant-receiving nipple, sealing means housed inside said nozzle and engaging said nipple when inserted to prevent rotation of said sealing means relative to said nipple, said sealing means being actuated by rotation of said nozzle relative to said nipple to move forward against said nipple and form a seal, and ported valve means axially slideable in said nozzle but rotating therewith, said valve means abutting said sealing member and said sealing member having ports positioned to register with said valve ports only after said seal has been formed.
12. Lubricating apparatus including a nozzle having means for receiving and retaining a lubricant-receiving nipple, and sealing means housed inside said nozzle and engaging said nipple when inserted to prevent rotation of said sealing means relative to said nipple, said sealing means being actuated by rotation of said nozzle relative to said nipple to move forward against said nipple and form a seal, and valve means in said nozzle positioned to open only after said seal has been formed.
13. Lubricating apparatus including a nozzle having means for receiving a lubricant-receiving nipple, and sealing means housed inside said nozzle and engaging said nipple when inserted to prevent rotation of said sealing means relative to said nipple, said sealing means being actuated by rotation of said nozzle relative to said nipple to move

forward against said nipple and form a seal.

14. Lubricating apparatus including a nozzle having means for receiving a lubricant-receiving nipple, and sealing means housed inside said nozzle and actuated by rotation of said nozzle relative to said nipple to move forward against said nipple and form a seal.

15. Lubricating apparatus including a nozzle having means for receiving a lubricant-receiving nipple, and sealing means actuated by rotation of said nozzle relative to said nipple to move forward against said nipple and form a seal.

16. Lubricating apparatus comprising a gun, a discharge nozzle receiving lubricant from said gun, sealing and clamping means operated by relative rotary and axial movement of parts carried by said nozzle to clamp a receiving nipple and form a seal therewith, and a single handle part for operating said sealing and clamping means.

17. Lubricating apparatus comprising a

gun, a discharge nozzle receiving lubricant from said gun, sealing and clamping means operated by relative rotary and axial movement of parts carried by said nozzle to clamp a receiving nipple and form a seal therewith, means for operating said sealing and clamping means by rotation of said nozzle about its own axis, a valve in said nozzle, and means for opening and closing said valve by rotation of said nozzle.

18. Lubricating apparatus including a lubricant expelling gun for engagement with a lubricant-receiving nipple directly and rigidly carrying a generally aligned nozzle presenting a valved coupling including a reciprocable sealing part and a deferred action rotary valve reciprocable with said sealing part during the coupling and uncoupling operations.

In testimony whereof, I have signed my name to this specification.

BENJAMIN F. HUBBELL.
